US00D852809S

(12) **United States Design Patent** (10) **Patent No.:** **US D852,809 S**
Rad et al. (45) **Date of Patent:** **** Jul. 2, 2019**

(54) **DISPLAY SCREEN OR PORTION THEREOF WITH A GRAPHICAL USER INTERFACE OF AN ELECTRONIC DEVICE**

(71) Applicant: **Tinder, Inc.**, West Hollywood, CA (US)

(72) Inventors: **Sean Rad**, Los Angeles, CA (US);
Andrew Rudmann, Los Angeles, CA (US)

(73) Assignee: **Match Group, LLC**, Dallas, TX (US)

(**) Term: **15 Years**

(21) Appl. No.: **29/575,876**

(22) Filed: **Aug. 30, 2016**

(51) **LOC (11) Cl.** **14-04**

(52) **U.S. Cl.**

USPC **D14/485**

(58) **Field of Classification Search**

USPC **D14/485-495**

CPC **G06Q 50/01; H04L 51/32; G06F 3/0482; G06F 3/04817**

See application file for complete search history.

(57) **CLAIM**

The ornamental design for a display screen or portion thereof with a graphical user interface of an electronic device, as shown and described.

DESCRIPTION

The FIGURE is a front view of a display screen or portion thereof with a graphical user interface of an electronic device.

The broken lines showing an electronic device display screen or portion thereof and elements of the graphical user interface represent environment and form no part of the claimed design.
